(57) **CLAIM**

The ornamental design for a display screen with animated graphical user interface, as shown and described.

DESCRIPTION

FIG. 1 is a front view of a display screen with an animated graphical user interface showing a first image which is part of a sequence showing our new design; and, FIG. 2 is a second image thereof.

The outer perimeter broken line showing of the display screen and all other broken lines showing portions of the graphical user interface are for the purpose of illustrating portions of the article and form no part of the claimed design.

The appearance of the animated images sequentially transitions between the images shown in FIGS. 1-2. The process or period in which one image transitions to another forms no part of the claimed design.
